[57] CLAIM

The ornamental design for a vehicle tire, as shown and described.

DESCRIPTION

FIG. 1 is a right side elevation view of the vehicle tire showing the design;

FIG. 2 is a front elevation view thereof; and

FIG. 3 is a perspective view of a tire showing our new design, it being understood that the tread design is repeated uniformly throughout the circumference of the tire and the opposite side is the same as that shown.

FIG.1

FIG. 2

FIG. 3
